UNITED STATES PATENT OFFICE

WILLIAM M. DUNCAN, OF ALTON, ILLINOIS

FURNACE GRATE

Application filed September 17, 1926. Serial No. 136,052.

This invention relates to improvements in furnace grates, and more particularly to a mechanically driven grate adapted to feed ashes and other residual matter from the bottom of a furnace. The preferred form of the invention comprises grate members located adjacent to each other and rotating in opposite directions to draw the residual matter through the grate structure.

- 10 One of the objects of the invention is to forcibly remove the ashes from the bottom of a furnace, so that the ashes will not interfere with the admission of air to the bottom of the fuel bed. The grate members can be 15 rotated at any desired speed to remove the ashes at the desired rate, and the air can be forced under pressure through the grate to provide for a high rate of combustion in the furnace.
- 20 Another object is to produce a grate of this kind having its elements so arranged that the air can freely enter through the grate while the ashes are being withdrawn. A further object is to distribute the air at the grate so 25 as to provide for substantially uniform combustion in the fuel adjacent to the grate.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

40 Fig. I is a horizontal section through the combustion chamber of a furnace, showing a grate constructed in accordance with my invention.

Fig. II is a vertical section approximately through the center of the furnace, showing 45 a portion of the grate in elevation.

Fig. III is a vertical section on the line III-III in Fig. II.

Fig. IV is a side view, partly in section, illustrating the gearing whereby the grate 50 members are rotated.

Fig. V is a detail view showing one of the grate wheels.

Fig. VI is a fragmentary plan view illustrating a modification.

Fig. VII is a longitudinal section of one 55 of the grate members shown in Fig. V.

The furnace shown by Figs. I to IV comprises a combustion chamber 1 above an ash pit 2, the latter having an inlet 3 for air under pressure and a sealing plate 4 extending into a body of water 5 to prevent leakage 60 of air from the ash pit.

The grate structure shown in Figs. I to V comprises a series of horizontal shafts 6 arranged parallel with each other and rotatably mounted in bearings 7. Each shaft 6 has a non-circular portion between its ends, and a row of circular grate wheels 8 is mounted on the non-circular portion of each shaft. Each of said wheels has a toothed periphery, 70 a central aperture conforming to the non-circular portion of the shaft, and a boss 9 on one side (Fig. V) whereby the peripheral portion is spaced from an adjacent grate wheel. 75

Gear wheels 10 are secured to the respective shafts 6, the gear wheel on each shaft being in mesh with the gear wheel on an adjacent shaft, so as to rotate the adjacent shafts in opposite directions. The driving means includes a pulley 11 fixed to one of the shafts 6, and this pulley is rotated continuously by any suitable power mechanism.

The peripheral projections, or teeth, on each row of grate wheels 8 are adjacent to but separated slightly from the corresponding projections on an adjacent row, and when these wheels are rotated in opposite directions, as indicated by arrows in Fig. III, the downwardly moving side of one row of 90 wheels will cooperate with the downwardly moving side of an adjacent row to forcibly draw residual matter through the grate.

Fuel-supporting baffles 12 are located immediately above the adjacent rising sides of the rows of grate wheels. The baffles shown in Figs. I and III are stationary bars extending across the bottom of the combustion chamber and provided with apertures 13 for the delivery of air to the fuel above said bars. 100

Since the grate wheels 8 are separated from each other, as shown in Figs. I and II, air can freely rise between the wheels. The baffles 12 aid in the distribution of the air by preventing the delivery of an undue volume of air between the rising sides of the rotary grate wheels, and they also separate the ashes and fuel from these rising sides.

Figs. VI and VII illustrate conical grate members 8' fixed to shafts 6' provided with gear wheels 10' whereby adjacent grate members 8' are rotated in opposite directions. A driving pulley 11' is fixed to one of the shafts 6'. The grate members 8' are hollow, as shown in Fig. VII, and they have peripheral projections 14 which force the residual matter through the grate structure. Apertures 15 are formed in the grate members 8' to provide for the admission of air through these members.

The grate members 8' are arranged around a central core 16, and each of said grate members has a trunnion 17 extending from its inner end and mounted in the central core, as shown in Fig. VII. Baffle bars 12' are located above the rising sides of adjacent grate members 8'.

I claim:

1. In a furnace grate, rotatable fuel-supporting members located adjacent to each other to form a grate, a driver whereby said adjacent members are rotated in opposite directions to force residual matter through the grate, and fuel-supporting baffles each located immediately above rising portions of two of the rotating fuel-supporting members.
2. In a furnace grate, rotatable fuel-supporting members located adjacent to each other to form a grate, a driver whereby said adjacent members are rotated in opposite directions to force residual matter through the grate, and fuel-supporting baffles each located immediately above rising portions of two of the rotating fuel-supporting members, said baffles being remote from the downwardly moving portions of the rotating fuel-supporting members, so as to permit free discharge of the residual matter.
3. In a furnace grate, rotatable fuel-supporting members located adjacent to each other to form a grate, a driver whereby said adjacent members are rotated in opposite direction to force residual matter through the grate, and fuel-supporting baffles each located immediately above rising portions of two of the rotating fuel-supporting members, said baffles being provided with apertures for the delivery of air therethrough.

4. In a furnace grate, circular fuel-supporting members located adjacent to each other, driving means whereby said adjacent circular members are rotated in opposite directions so that the downwardly moving side of each of said members will cooperate with the downwardly moving side of an adjacent

member to draw residual matter through the grate, and fuel-supporting baffles located above the center lines of the spaces between the adjacent rising sides of said circular fuel-supporting members.

In testimony that I claim the foregoing I hereunto affix my signature.

WILLIAM M. DUNCAN.
